PERMUTATION LOCK

Carl Rapp, Brooklyn, N. Y.

Application January 17, 1935, Serial No. 2,209

9 Claims. (Cl. 70—53)

My invention relates to keyless locks, and in particular to permutation locks, and is adapted for application to brief-cases, overnight bags, suitcases and like outfits, the usual clasp being applied to the flap or cover while the lock proper is secured to the body of the article. Again, my lock may be made in such sizes as to be adapted for other uses, such as closets and small trunks, etc.

10 The invention comprises an improved permutation lock, and one object of the invention is to provide a simple, strong, efficient and practical device of this character that is adapted to be used on small bags which require a lock. The lock is 15 so constructed that the various parts may be assembled and placed in position and made secure to the article without other fasteners which secure the same to the article. The lock secures the contents while being checked or in the hands 20 of the porter.

25 The prime object of the invention is to provide a lock that may be readily opened and closed without the use of a key or other device for opening the lock, yet such lock holding the contents 30 of the article safe and secure. In the illustration, the catch is shown as being of one piece 35 T-shaped, but it may be advantageous and desirable in some instances, such as with suitcases and overnight bags, to have the part spring hinged so that as soon as the bolt releases the catch, the 40 same will fly open and back on itself so as to be out of the way. In all stiffened bags, it may be even preferable to have it so made, but for use on brief-cases, it is preferable to have the T-shaped clasp in one piece as shown on the illustration. As has been noted, the lock may be 45 made for heavier duty, for instance, on closets and such light doors, in such places as it would contain household things and be secure when 50 locked, but at the same time handy and easily opened.

With the foregoing and other objects in view, the invention resides in the novel arrangement and combination hereinafter described and 45 claimed, it being understood that changes in the precise embodiment of the invention herein disclosed may be made within the scope of what is claimed without departing from the scope of the invention.

50 Other objects and advantages of my invention will be apparent as it is better understood by reference to the following specification when read in connection with the accompanying drawing, in which: Fig. 1 is a face view of my invention as it 55 would appear on a brief-case, overnight or other

bag; Fig. 2 is a detached rear view of the locking member; Fig. 3 is a view of the inside, with the cover shown in dotted lines, with the hub of the lower left-hand cog wheel in section, and the lower central cog wheel and its hub omitted for clearness, both of these cog wheels being indicated in outline in broken lines; Fig. 4 is a detached detail sectional view taken on the line 4—4 of Fig. 3; Fig. 5 is a like section showing how the member may assume a locked position, and Fig. 6 shows my invention applied to an overnight bag.

Referring to Figs. 1, 2 and 3, it will be seen that the base plate 10 is provided with upwardly extending flanges 11, over which the cover snugly fits, and said base plate is provided with a plurality of upwardly extending projections 12, 13 and 14, which extend upwardly and cooperate with slots 15, 16 and 17 in the bolt plate 18 that reciprocates back and forth on the base plate, 20 while at the upper part of said plate the projections 19 and 20 extend through elongated inclined slots 21 and 22, which slots are parallel with the slots 15, 16 and 17, above referred to. The bolt plate 18 houses the hubs of three wheels 23, 24 and 25, while the hub of each wheel is provided with suitable slots 27, 28 and 29. When the combination has been properly applied to the lock the slots in the plate 18 and the slots in the hubs of the wheels will be in proper alignment 30 for the withdrawing of the bolt 31 from the clasp; otherwise the hubs will be as shown in Fig. 3, wherein it will be seen how impossible it would be to operate the bolt 31. The bolt plate 18 for convenience of operation is provided with a thumb 35 member 30, while its opposite end is provided with the locking bolt 31. A spring 32 causes the bolt plate 18 to remain in the forward or locked position. Said plate on its lower edge has downwardly extending fingers 33, 34 and 35, which 40 limit the forward movement of the plate 18.

The base plate 10 has openings in the plate which house the hubs of cogs 36, 37 and 38. Said hubs are provided with teeth 39, into which a depressed spring finger 43 of a curved spring 44 fits and holds the respective wheel to any combination that may be desired. Any member may be used for the combination, and when the proper members appear through the windows 42, all that is necessary for the operator to open the receptacle is to withdraw the finger member 30, whereupon, as has been stated, all the parts being in alignment, the bolt 31 will become detached from the catch and the receptacle ready to be opened.

As shown in Fig. 2, the face plate 40 is pro-

vided with a depending edge 40' which entirely encloses the base plate, and as shown in Figure 1, is also provided with a slot 41 for the catch 41' to protrude through, while to the right of said slot are three windows 42 which outline the particular members, as shown; the lock is set for 642, and if this is the proper combination, all that is necessary to open the lock is to withdraw the finger member 30 to the right and the same will 10 open. To close or open the lock, it is necessary to operate the cogs 36, 37 and 38 by moving the protruding teeth that extend below the lower edge of the face plate 40. It is, of course, necessary to apply sufficient force to overcome the 15 spring action of spring 44 and to effect relative sliding movement between notch 43 and teeth 39. As before noted, when the several wheels have been turned to the selected combination the slots in the hubs of wheels 23, 24 and 25 will be in line 20 with the projections 15, 16 and 17, as they appear in Fig. 2 (which is the reverse or under side). Thus it will be seen that a very secure and reliable lock may be provided, yet the same may be opened by the proper person knowing the combination in the shortest possible time, with all 25 convenience and haste.

Again, it may be desired to change the existing combination (642) to some other more desirable one. To do so, the various parts of the lock 30 must be in the position as shown in Fig. 2. That is to say, that the slots 27, 28 and 29 in the hubs of wheels 23, 24 and 25 must be in alignment with the projections 12, 13 and 14. The withdrawing of the thumb member 30, the wheels 23, 24 and 25 35 are withdrawn from meshing with the wheels 36, 37 and 38. The latter being now free may be turned so as to again set some new combination; when this has been done, the thumb member is released and the wheels 23, 24 and 25 again allowed to mesh with wheels 36, 37 and 38, presenting the new combination. Thus it will be seen that with the arrangement as shown, the combination may be from 1 to 1000. Yet by the enlargement of the lock so as to accommodate 40 another pair of wheels, the combination may be from 1 to 10,000. The changing of the combination is very simple, and thus may be changed at any time for any reason and yet be perfectly safe.

50 I have shown the projections 12, 13 and 14 struck up from the bottom of the base plate 10, although they may be affixed in position in any other manner. So too, I have also struck up the projections 19 and 20 from the base plate. 55 Again, by striking up the opening for the hubs of wheels 36, 37 and 38, I provide an additional bearing 45 for the wheels, as well as bringing them to proper cooperation with wheels 23, 24, and 25. In this turned up bearing 45, I provide a recess so as to allow the finger 43 of the spring 44 to snap into the teeth 39 and thereby hold the wheel against accidental movement.

Thus it will be seen that when the wheels have registered the desired numbers through the windows, the operator draws the thumb member to the right and thereby releases the catch, the bolt plate moving rearwardly and upwardly by reason of the various slots 21, 22, 15, 16 and 17, also by reason of the slots 27, 28 and 29 in the hubs of the 65 wheels 23, 24 and 25 being coincident with the projections 15, 16 and 17 which permits the bolt plate 18 to be withdrawn. As noted, should any one of the several slots be not in alignment with the projections, the bolt plate cannot be moved. 70 75 It is absolutely essential that the parts be in their

proper position for the various cooperating parts to perform their functions.

As shown in Fig. 4, the base plate 10 is shown with the upturned flange 45 into which the toothed hub 39 of the wheel 36 fits, and the finger 43 of the spring 44 to fit into one of the teeth of the wheel which releasably locks them in any desired position. By reason of my method of making the parts 12, 13, 14, 19 and 20 a part of the base plate 10 cooperate with the adjacent bolt 10 plate 18, it thereby avoids the necessity of extra parts. Likewise, as has been noted, the upturned flange 45 also does away with an extra part for holding the wheels 36, 37 and 38 in a stationary position. It will be noted that when the bolt plate 18 is forced to the right, the two sets of wheels become disengaged, but the spring fingers 43 hold the lower set in place so that when the thumb member 30 is released the two sets of wheels return again to cooperative working position.

The lock is neat, small and easily assembled and placed on any particular receptacle with no visible means of attachment, making it a very attractive and safe lock for the particular purpose.

Having fully described my invention, what I claim as new, and desire to secure by Letters Patent, is:—

1. A permutation lock of the character described comprising a locking catch including a central body, a manually operable trigger at one end of said body, and a latch-engaging finger at the other end of said body, said body comprising a non-rotatable portion and a rotatable portion, a multi-part slot having one part thereof in each of said portions, said catch being movable only when said rotatable portion is so positioned relative to said non-rotatable portion that said slot parts are juxtaposed and in alinement.

2. A permutation lock of the character described comprising a catch member, a casing substantially enclosing said catch member, a manually operable trigger at one end of said member projecting from said casing, a latch-engaging finger at the other end of said body, said body comprising a non-rotatable portion and a plurality of rotatable portions mounted thereon, said non-rotatable portion being provided with a slot adjacent to each of said rotatable portions, said rotatable portions being each provided with a slot adapted to be alined with the corresponding slot of the non-rotatable portion to form an extension thereof, said catch member being movable only when said several slots are in alinement, and means extending from said casing for effecting rotation of said rotatable portions in predetermined manner.

3. A permutation lock of the character described comprising a casing, a guide member extending from said casing wall, a catch slidably mounted in said casing and having a slot adapted to receive said guide member, said slot being substantially coextensive with said guide member, and means movably mounted on said catch and having a slot adapted to be alined with said first-named slot to form an extension thereof when said means is in predetermined position, whereby sliding movement of said catch is possible only when said slots are alined.

4. A permutation lock of the character described comprising a casing, a catch member arranged in said casing, said catch member being provided with a multi-part slot, a finger extending from said casing into said slot, a gear member rotatably mounted on said catch member, one

part of said slot being formed in said rotatable gear member, whereby relative movement between said finger and said slot-defining parts is possible only when said gear member is in such position that said slot parts are juxtaposed and in alinement.

5. The construction defined in claim 1, wherein said rotatable portion consists of a gear member having a hub portion, the slot of said rotatable portion being arranged in said hub portion, and means adapted to coact with said rotatable portion to effect stepwise movement thereof.

6. The construction defined in claim 3, wherein said first-named slot is arranged obliquely to the longitudinal axis of said catch, and supplementary means for guiding the sliding movement of the catch and comprising guide slots disposed in parallel relationship with said first-named slot.

7. A permutation lock of the character described comprising a casing, a catch member arranged in said casing, said catch member being provided with a plurality of spaced journal openings, a slot extending obliquely into the body of

said catch member from each of said openings, a gear member journaled in each of said openings and provided with a slot adapted to be aligned with and to form an extension of the corresponding body slot when said gear member is in predetermined position, a plurality of fingers extending from said casing and normally severally received in one of said body slots, and manually operable indicia-bearing means extending to the exterior of the casing for moving said gear members to said predetermined positions.

8. The construction defined in claim 7, spring means acting on said catch and tending to retain said fingers in the corresponding body slots, relative movement of said fingers from said body slots into said gear slots against the action of said spring means being possible only when said gear members are in said predetermined positions.

9. The construction defined in claim 7, said last-named means consisting of a plurality of gear members mounted for rotation only in said casing.

CARL RAPP.
